SEWING MACHINE ATTACHMENT

David L. Bacon, North Haven, Samuel P. Caldwell, Hamden, and William L. Barmmer, Stratford, Conn., assignors to The Greist Manufacturing Company, New Haven, Conn., a corporation of Connecticut

Application October 2, 1940, Serial No. 359,384

14 Claims. (Cl. 112—160)

This invention relates to sewing machine attachments, and more particularly to an attachment designed to perform what is known as a zigzag or crisscross stitching operation. In devices for performing an operation of this character, it is necessary that the cloth or material being stitched be moved laterally between certain of the stitching operations, that is, be given a lateral movement during the time that the sewing machine needle is raised out of contact with the material. In connection with devices of this character, it is desirable that the device be adjustable so that the lateral movement given the cloth may be varied over a relatively wide range, so that with the same attachment a very fine or a very coarse zigzag stitch may be effected and also any stitch in between these two extremes.

It is also desirable in some cases to make a fancy zigzag stitch. This may be effected, for example, by providing the device with an adjustment whereby the cloth will not be moved laterally after every stitching operation of the sewing machine needle, but only after certain of such operations, for example, every alternate stitching operation, although it will be understood that the number of stitching operations between lateral movements of the material may be varied. It will be understood that in the attachment herein described, the feed or forward movement of the cloth is obtained by the usual feed mechanism on the sewing machine and that when the mechanism is adjusted for fine or coarse zigzag stitching, the feed of the machine will usually be correspondingly adjusted. It is also possible, with the attachment herein shown, to adjust the tension of the thread so that one of the threads, the lower, for example, may be pulled through the cloth to show on the face thereof, and thereby make a fancy stitch.

One object of the invention is the provision of a sewing machine attachment for the production of zigzag or crisscross stitchings which will operate efficiently and which will be capable of a wide variety of uses.

Another object of the invention is the provision of a zigzag sewing machine attachment relatively simple in construction and which will at the same time be capable of a relatively wide range of adjustments for various types of work.

A further object of the invention is the provision of a sewing machine attachment of the character described which may be adjusted to make a zigzag stitch between each of the stitching operations of the sewing machine or between

every alternate stitching operation or a plurality of stitching operations, as desired.

A still further object of the invention is the provision of a sewing machine attachment for zigzag or crisscross stitching which may be relatively economical to manufacture and which, at the same time, will be efficient in operation and capable of use to effect a wide variety of stitching operations.

To these and other ends the invention consists in the novel features and combinations of parts to be hereinafter described and claimed.

In the accompanying drawings:

Fig. 1 is a side elevational view of a sewing machine attachment, embodying our invention;

Fig. 2 is a similar view, taken from the other side of the attachment;

Fig. 3 is a top plan view of the attachment;

Fig. 4 is a sectional view on line 4—4 of Fig. 2;

Fig. 5 is a sectional view on line 5—5 of Fig. 2;

Fig. 6 is a sectional view on line 6—6 of Fig. 3;

Fig. 7 is a sectional view substantially on line 7—7 of Fig. 6;

Fig. 8 is a detail elevational view, partly in section, on line 8—8 of Fig. 3;

Fig. 9 is a detail sectional view on line 9—9 of Fig. 8;

Fig. 10 is an end elevational view of the parts shown in Fig. 8;

Fig. 11 is a sectional view on line 11—11 of Fig. 8;

Fig. 12 is a perspective view of the operating lever;

Fig. 13 is a perspective view of the pivoted foot of the attachment;

Figs. 14, 15, 16 and 17 are views showing various kinds of stitching of which the attachment is capable;

Fig. 18 is a side elevational view of a modified form of our device;

Fig. 19 is a plan view of the pivoted foot of the mechanism shown in Fig. 18, and

Fig. 20 is an enlarged sectional view on line 20—20 of Fig. 19.

To illustrate a preferred embodiment of our invention, we have shown a zigzag attachment comprising a frame member 10, comprising spaced side members 11 and 12 which, as shown at 13, are raised at their central portions to provide bearings for a rotatable shaft 14. This frame member is provided with a forwardly extending portion 15, to which may be secured an adapter or attaching member 16, by which the device may be attached to the presser bar 17 of a sewing machine in the usual manner.

Secured to the shaft 14 is a hub member 18 having rigidly mounted thereon a rotatable cam member 19. This member is made of two parts, 20 and 21, which parts, as shown more especially in Figs. 3 and 4, are similarly formed and provided with spaced teeth or cam portions 22, having bevelled side edges 23. The two members 20 and 21 are secured together back to back with the teeth of one alternating with those of the other so that the result is a member with laterally displaced cam surfaces on each side of a center plane. In this manner, a sharp edge of a tooth of one cam member joins a similarly sharp edge of a tooth of the adjacent cam member so that at this point the periphery of the member will be of very slight thickness.

Pivoted upon the shaft 14 is actuating or operating lever 25, provided with a bifurcated slotted end 26, and adapted to be connected to the needle bar 27 in the usual way so that the lever 25 will be reciprocated in a vertical plane by the up and down movements of the needle bar.

Pivoted upon the lever 25 is a pawl 28, the end 29 of which is adapted to engage with either of ratchet wheels 30 and 31 fixed upon the shaft 14 and spaced apart by a spacing member 32.

The pawl 28 is pressed into engagement with these ratchet wheels by a spring 33 and the pivotal connection of this pawl with lever 25 is shown more especially in Fig. 11. As shown in this figure, the pawl 28 is rigidly secured to the reduced portion of a knurled button 35, slidably mounted on a pin 36 secured to the lever 25. This pin is provided with a head 37 and the button 35 is recessed as shown at 38 to receive the head of the pin when the pawl is moved outwardly. It will be understood that the operator, by grasping the button 35, may move this button and the pawl 28 away from the lever 25 so as to effect the engagement of the pawl with the outer ratchet wheel 30. The pawl will be maintained in this position by the downwardly turned end 39 of the spring 33 and the lateral face of the spacing member 32. A spacing member 40 may also be employed between the pawl 28 and the lever 25, so that the pawl will correctly register with the inner ratchet 31, when it is desired to have it in engagement with this ratchet wheel.

It may here be stated that the ratchet wheels 30 and 31 are provided with a different number of teeth. In the form shown, the ratchet wheel 30 is provided with 12 teeth and the ratchet wheel 31 with 24 teeth, although the number of teeth may be varied as desired. With this arrangement, it will, of course, be obvious that the movement of the ratchet wheel 30 through one tooth space will result in a movement of the shaft 14 and cam member 19 through a greater angle than that effected by movement of the ratchet wheel 31, through a distance of one tooth space. As the lever 25 would normally be given the same stroke by the needle bar of the sewing machine, regardless of which ratchet wheel is employed, it would tend, in the form illustrated, to move the ratchet wheel 31 through a distance equal to two tooth spaces upon each stroke of the needle bar. A mask 41 is provided to cover a portion of the teeth of the ratchet wheel adjacent the point of engagement of the pawl 28 so that the pawl, when in position to engage the ratchet wheel 31, will move over this mask during a part of its movement and thus be in engagement with the teeth of the pawl only during the remainder of its movement and, therefore,

will move the ratchet wheel 31 through a distance equal to one tooth space at each stroke of the lever 25. The mask 41 may be provided upon a sheet metal plate-like member 42 secured to the frame of the attachment at 43. Thus, in effect, a lost motion connection is provided between the pawl 28 and the ratchet wheel 31. As illustrated, therefore, when the pawl 28 is in engagement with the ratchet wheel 31, the shaft 14 will be moved through an angle only one-half as great as when the pawl is in engagement with the ratchet wheel 30.

A pin 45 is secured to the portion 15 of the frame and upon this pin is pivoted the shank 46 of a foot member shown more especially in Fig. 13. This foot member is provided with the usual downwardly stepped forward portion or foot 47, having an elongated needle slot 48 therein and the shank portion of the member is provided with a V-shaped slot or opening 49 adjacent its rear end. A spring 50 acting against a washer 51 on the pin 45 urges the shank 46 of the foot member toward the part 15 of the frame, but flat contact of these two parts is prevented by a pin 52 secured to the member 15 and having its head disposed between this member and the shank 46. It will be observed that the foot member is thus arranged to swing about two axes relatively to the frame, so that it may adjust itself to any unevenness in the cloth or the bed of the machine. The forward portion 47 of the foot member may swing upwardly and downwardly about the pin 52 about an axis transverse to the forward travel of the material and it also may swing or rock from side to side about an axis longitudinally of the attachment. This freedom of movement given the foot is, of course, in addition to its lateral pivotal motion about the pin 45 and enables the foot to accommodate itself at all times to the material and the bed.

Pivoted to the rear portion of the frame member at 55 is a lever 56, shown more especially in Fig. 12, which lever extends forwardly below the shank portion 46 of the foot and is provided with a slot 57 to receive the pin 45, the forward portion of the lever being held in position by the washer 51, while the slot provides for a swinging movement of the lever with respect to the pin 45. The lever is provided with an upwardly displaced portion 58 to receive the rivet 55, and with a vertically projecting end portion 59, so that, as shown in Fig. 12, this member is substantially L-shaped in form. It is also provided with a pair of pins 60 upon which are mounted rollers 61 in spaced relation so that one of these rollers lies upon each side of and is engaged by the peripheral cam surfaces of the cam member 19.

This lever 56 is also provided with a longitudinally extending slot 63, through which projects a pin 64 secured to a plate 65 positioned at the lower surface of the lever. The plate 65 is provided with a longitudinally extending slot 66 which receives a pin 67 securing the plate to the lever 56, but permitting longitudinal adjustment between these two members, as limited by the length of this slot. While, as will be explained hereinafter, the lever 56 and plate 65 move as one member during the operation of the device, this longitudinal adjustment between the two provides for adjustment of the pin 64 which projects through the slot 63 and into the V-shaped recess 49 provided at the rear end of the shank 46.

The plate 65 is also L-shaped in form, being provided with an upstanding rear end portion 68 in which portion is rotatably mounted an adjust-

ing nut 69 which threadedly receives a screw 70 secured to the portion 59 of the lever 56. The adjusting nut may be provided with a series of notches or recesses 71 adapted to be engaged by a detent or index member 72 on a spring 73 secured to the plate 65. It will be apparent that as the nut 69 is rotated, the part 68 will be caused to approach or recede from the part 59 and, therefore, will adjust the pin 64 forwardly or rearwardly with respect to the lever 56, and also with respect to the slot 49. The recesses 71 are evenly spaced upon the nut 69 and the detent 72 cooperating with these recesses provides for accurate adjustment of the pin 64 and also for a very fine adjustment of this pin. For example, if the screw 70 contains 40 threads to the inch and if ten recesses 71 are provided on the adjusting nut 69, the pin may be given adjustments as fine as .0025 of an inch.

It will be apparent from the foregoing description that as the sewing machine to which the attachment is connected is operated, the up and down movements imparted to the lever 25 will, through the ratchet wheels 30 and 31, impart a rotating step by step movement to the shaft 14 and cam member 19. This cam member, operating between the rollers 61 will cause a lateral oscillatory movement to be imparted to the lever 56, this movement taking place about the pivot pin 55. As the plate 65 moves with the lever 56, the pin 64 will be given an oscillatory movement and as this pin strikes the sides of the V-shaped slot 49 it will effect a lateral oscillating pivotal movement of the foot 47 about the pivot pin 45, and the foot 47, being in contact with the material, will cause the material to move laterally so as to effect a zigzag stitch.

It will also be seen that, as the slot 49 is of tapering or V-shaped form, the movement of the pin 64 longitudinally of the device by means of the adjusting nut 69 (which moves the plate 65 to which the pin 64 is secured) will vary the throw given to the foot 47, both because when the pin is at the wider portions of the slot there will be considerable lost motion between this pin and the edges of the slot and also because the point of attack of the pin 64 upon the shank of the foot member will be varied to some extent with respect to the pivot pin 45. The maximum throw of the foot occurs when the pin 64 is at the forward end of the slot 49 where no lost motion occurs and adjustment in the opposite direction can be made until the pin 64 no longer contacts the sides of the recess 49 and thus giving the foot no movement at all, in which event straight sewing is effected.

When the pawl 28 is in engagement with the outer ratchet wheel 30, as shown in Fig. 3, the cam member 19 is moved through a distance substantially equal to the spacing between the high points of two adjacent peripheral cam portions, so that the cloth is given a lateral movement for each stitch of the machine, thus effecting an angular zigzag stitch, shown, for example, in Fig. 14. The operator, by grasping the button 35, may turn the pawl slightly until it is out of contact with the ratchet 30 and move it inwardly until it is in engagement with the ratchet wheel 31. As this ratchet wheel is provided with twice as many teeth as the ratchet 30 and as the mask 41 prevents the engagement of the pawl with the ratchet wheel during a part of its movement, the cam member 19 will, during one stroke of the needle bar, be moved through only one-half the former distance, or through a distance equal to one-half

of the distance between two adjacent cam portions. In this instance, the cloth will be given a lateral movement, not between every stroke of the needle bar, but between every two strokes of the needle bar, which will effect the stitching shown in Fig. 15 of the drawings. This is due to the fact that the periphery of the cam member is so shaped that the lateral movement takes place during the last half of a full-step rotative movement of the cam from one high point of the cam to the next, and hence when the cam is moved only through the first half of this step so that the rollers pass from the high point of one of the teeth to the point opposite the junction of adjacent teeth, no movement of the lever 56 results. By adjusting the pin 64 either of these stitches may be made as fine or coarse as desired up to the limits of the attachment.

By reducing the tension of the bobbin thread, 20 fancy zigzag stitches, as shown in Figs. 16 and 17, may be effected. In such event, the lower thread is pulled through to some extent by the upper thread, as shown in these figures. Thus, by adjusting the amount of lateral throw given to 25 the foot, by adjusting the sewing machine feed, by adjusting the tension of the lower thread, and by the adjustment of pawl 28 to positions to engage a plurality of ratchet wheels to vary the 30 number of stitches with respect to the number of lateral movements of the cloth, a great variety of work may be effected.

It may be advantageous to do plain sewing at 35 times without removing the attachment from the machine. For this purpose, the pawl 28 is provided with a V-shaped notch 75 in the end contacting the ratchet wheels. The pawl may, therefore, be placed in the position in Fig. 10, where the V-shaped notch engages the spacing member 32, and is held out of engagement with either 40 of the pawl members so that no motion is given to the foot member 46, and plain sewing results. It may also be desirable to provide means for setting the cam member 19 at the beginning of 45 the sewing operation. For this purpose, the shaft 14 may be provided with a knurled knob 76 by which this shaft may be turned independently of movement of the lever 25.

It may also be desirable to provide indicating 50 means to indicate the adjustment of the plate 65 and pin 64. For this purpose, graduating marks 77, shown in Fig. 1, are placed upon the plate member 65 and an index mark 78 is placed upon the lever 56. This index mark will cooperate with the graduation to indicate at once to the 55 operator the setting of the pin 64 and, therefore, the amount of lateral throw or zigzag motion given to the foot member 46.

It will be understood that the device may also 60 be employed to stitch a cord, a band, or braid, upon a piece of material, and for this purpose a guide member 79 is shown as secured to the foot member 47 by means of the screw 80, the guide member being provided with an opening 81 to span the needle opening 48 and also to span a flexible cord-guiding member 82 also secured to the foot 47. The guide member is also provided with a plurality of cloth guiding slots 83.

In Figs. 18 to 20 of the drawings, we have 70 shown a modified form of the invention which in some respects is of simpler construction than the attachment previously described. In this modification, the lever 56, the plate 65 and the foot member 46 are replaced by a single member which is pivoted to the frame and which carries the presser foot thereon. This member is shown at

90, is pivoted to the frame at 91, and carries at its forward end a downwardly offset presser foot 92. As shown in Fig. 19, it is provided with a slot 93 which receives a guide pin 94 secured to the forward portion of the frame, so that the member 90 will be properly guided in its movement. It will be understood that the frame member 95, the cam member 96, the operating lever 97 and associated parts are like those described in connection with the frame of our invention shown in Figs. 1 to 13.

The member 90 is provided with a pair of up-standing ears 98, provided with open-ended slots 99, within which rotatably rests a right and left-hand threaded screw 100, having an adjusting knob 101 upon one end. Threadedly mounted upon the right and left-hand threads of this screw respectively, are sleeves 102, to which sleeves are secured downwardly projecting pins 103, having lateral sliding motion in slots 104 in the member 90. Also secured to these sleeves and projecting upwardly therefrom are pins 105, which carry rollers 106, adapted to be engaged by the cam member 96. The screw 100 is held in position by means of a clamping member 107 which is secured to the plate 90 and engages the reduced central portion of the screw between the threads so that longitudinal movement of the screw is prevented. Thus, it will be seen that rotation of the screw serves to move the rollers 106 toward and away from each other, depending on the direction of rotation. This causes the rollers to move closer to or further from the cam 96, so as to adjust the lateral throw imparted to the member 90 by the cam, due to the fact that there will be an amount of lost motion between the cam and rollers, depending upon the amount of separation of these rollers.

The adjusting knob 101 may be provided with a number of regulated spaced notches 108 within which is adapted to engage a detent 109, arranged at the end of a spring 110 secured to the lower surface of the member 90, so that the knob 101 may be set and releasably retained in any given position to which it is adjusted.

This form of our invention is capable of the same operations as the form first described, as it also is provided with the two ratchet wheels (not shown), and is capable of the same adjustments to vary the stitch.

While we have shown and described some preferred embodiments of our invention, it will be understood that it is not to be limited to all of the details shown, but is capable of modification and variation within the spirit of the invention and within the scope of the appended claims.

What we claim is:

1. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said connection including a pawl and a pair of ratchet wheels, and means for placing said pawl in cooperative relation with either of said ratchet wheels as desired.

2. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said connection including a cam wheel rotated in a step-by-step movement, means for

varying the length of said steps, and said cam wheel being so constructed that it is permitted an initial movement without effecting movement of said foot, whereby such variation effects a variation in the number of lateral movements relatively to the number of strokes of the needle bar.

3. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said connection including a cam wheel rotated in a step-by-step movement, and means for varying the length of said steps, said last-named means including a pair of ratchet wheels and a pawl to cooperate with either of said wheels selectively.

4. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said connection including a pawl and a pair of ratchet wheels, means for placing said pawl in cooperative relation with either of said ratchet wheels as desired, and means for placing said pawl in position in which it engages neither of said wheels.

5. An attachment for a sewing machine having a presser bar and a needle bar, said attachment comprising a frame, a foot movably connected to said frame for lateral oscillatory movements, means actuated by the needle bar of the sewing machine to effect movement of said foot including a cam wheel, said cam wheel comprising a pair of members each having outwardly facing spaced cam surfaces, and means for securing said members together in opposing back-to-back relation, with the cam surfaces of one member alternating with, and facing oppositely with respect to those of the other.

6. An attachment for a sewing machine having a presser bar and a needle bar, said attachment comprising a frame, a foot movably connected to the frame, means for effecting lateral oscillatory movements of said foot without advancing the same relatively to the frame, said means including a lever operable by the needle bar, a rotatable shaft actuated by the lever in a step-by-step movement, each step resulting from a stroke of the needle bar, means to vary the angle through which the shaft is turned during a single stroke of the lever, and connections between said shaft and foot operative to provide for initial movement of the shaft without effecting movement of said foot.

7. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said means including a cam wheel rotated in a step-by-step movement, and means for varying the length of said steps including a cooperating pawl and ratchet, means to hold said pawl from engagement with the teeth of the ratchet during a part of its movement, and connections between said cam wheel and said foot, said cam wheel and said connections being arranged to provide for an initial movement of said wheel without effecting movement of said foot.

8. A sewing machine attachment for zigzag stitching operations, comprising a frame, a foot

connected to the frame for lateral oscillatory movement, a lever pivoted to the frame, means actuated by the needle bar to move said lever on its pivot, and means connecting said foot to the lever whereby the former is oscillated by the latter, said connecting means comprising a slot of varying width in said foot and a pin carried by said lever and received in said slot.

9. A sewing machine attachment for zigzag stitching operations, comprising a frame, a foot connected to the frame for lateral oscillatory movement, a lever pivoted to the frame, means actuated by the needle bar to move said lever on its pivot, means connecting said foot to the lever whereby the former is oscillated by the latter, said connecting means comprising a slot of varying width in said foot and a pin carried by said lever and received in said slot, and said pin being adjustable longitudinally of the slot to vary the throw imparted to said foot.

10. A sewing machine attachment for zigzag stitching operations, comprising a frame, a foot connected to the frame for lateral oscillatory movement, a lever pivoted to the frame, means actuated by the needle bar to move said lever on its pivot, and means connecting said foot to the lever whereby the former is oscillated by the latter, said connecting means comprising a plate carried by said lever, a pin on said plate, and said foot having a slot in which the pin is received.

11. A sewing machine attachment for zigzag stitching operations, comprising a frame, a foot connected to the frame for lateral oscillatory movement, a lever pivoted to the frame, means actuated by the needle bar to move said lever on its pivot, and means connecting said foot to the lever whereby the former is oscillated by the latter, said connecting means comprising a plate carried by said lever, a pin on said plate, and said foot having a slot in which the pin is received, said plate being adjustable on said lever.

12. A sewing machine attachment for zigzag stitching operations, comprising a frame, a foot connected to the frame for lateral oscillatory movement, a lever pivoted to the frame, means

actuated by the needle bar to move said lever on its pivot, means connecting said foot to the lever whereby the former is oscillated by the latter, said connecting means comprising a plate carried by said lever, a pin on said plate, and said foot having a slot in which the pin is received, said plate and lever comprising L-shaped members having horizontally disposed body portions and upstanding spaced end portions, and means adjustably connecting said end portions for moving the pin relatively to the slot.

13. An attachment for a sewing machine having a presser bar and a needle bar, comprising a frame adapted to be connected to the presser bar, a foot movably connected to the frame, means connected to the needle bar for actuation thereby for effecting lateral oscillatory movements of said foot, said connection including a pawl and a pair of ratchet wheels, means for placing said pawl in cooperative relation with either of said ratchet wheels as desired, and means causing said pawl to pass idly over the teeth of one of said ratchet wheels during the initial part of its movement.

14. A sewing machine attachment for zigzag stitching operations, comprising a frame, a foot connected to the frame for lateral oscillatory movement, a lever pivoted to the frame, means actuated by the needle bar to move said lever on its pivot, means connecting said foot to the lever whereby the former is oscillated by the latter, said connecting means comprising a plate carried by said lever, a pin on said plate, and said foot having a slot in which the pin is received, said plate and lever comprising L-shaped members having horizontally disposed body portions and upstanding spaced end portions, and means adjustably connecting said end portions for moving the pin relatively to the slot, said last-named means including a threaded adjusting member whereby fine adjustments of said parts can be made.
